UNITED STATES PATENT OFFICE.

EPHRIAM J. SCOTT, OF PROVIDENCE, RHODE ISLAND.

SPRING-MOTOR.

1,121,944.

Specification of Letters Patent. Patented Dec. 22, 1914.

Application filed September 24, 1914. Serial No. 863,285.

To all whom it may concern:

Be it known that I, EPHRIAM J. SCOTT, a citizen of the United States, and resident of the city of Providence, in the county of Providence and State of Rhode Island, have invented certain new and useful Improvements in Spring-Motors, of which the following is a specification.

This invention relates to spring winding clutch mechanism for toys and the like, and has for its object to provide such a clutch mechanism of extremely simple and inexpensive construction and yet strong and durable and also practical in its operation.

With this and other objects in view, the invention consists of certain novel features of construction, as will be more fully described, and particularly pointed out in the appended claim.

In the accompanying drawings: Figure 1— is a plan view showing the mechanism inclosed between the walls of the casing. Fig. 2— is a sectional plan view of the mechanism. Fig. 3— is the winding key, on 10 the shaft of which the mechanism is mounted. Fig. 4— is a front view of one of the clutch members. Fig. 5— is a sectional side elevation of this clutch member. Fig. 6— is a view of the blank as cut from sheet 20 stock from which the drum or barrel is formed. Fig. 7— shows the arms of this blank bent up to form the drum on which the driving spring is wound. Fig. 8— is a front view of the drum member. Fig. 9— is a side elevation of the driving gear. Fig. 10— is a detail in perspective of the 25 casing between the walls on which the mechanism is mounted. Fig. 11— is a front view of the spring whose resilient fingers 30 press the driving gear into contact with the teeth of the clutch member.

Referring to the drawings 10 designates the casing which may be of any suitable material and is constructed preferably in a 45 rectangular form having apertures 11 through its side walls for receiving the shaft portion 13 of the winding key 14 and apertures 12 for receiving the jack shaft 15 on which the pinion 16 is mounted. A drum 17 50 is formed preferably by stamping a blank from sheet stock having a plurality of arms 18 as illustrated in Fig. 6. These arms are bent forward as illustrated in Fig. 7 and in the center of the plate is formed a square 55 hole 20 for the reception of the correspond-

ingly shaped shaft portions of the key 14. A clutch member 21 is also formed by drawing up a disk of sheet metal into cup form, the rear wall of the cup being provided with a plurality of perforations as at 22 for the 60 reception of the end portions of the corresponding arms 18 which are riveted or bent over therein, this said wall being also provided with a square opening 23 through which the body of the key is passed. The 65 edge portion of this clutch member is provided with ratchet teeth 24. The driving gear 25 of this mechanism is provided with a central circular bore to turn freely on the key shaft 13. This gear is also provided 70 with a plurality of apertures 27 adapted to register with and receive the teeth 24 of the clutch member 21 through which the gear is driven, and a flat spring 28 having a central aperture 29 and resilient fingers 37 positioned between the wall 30 and this gear is arranged to press the gear into contact with the teeth of the clutch member. One end 31 of the clutch spring 32 is secured to one of the arms 18 of the drum and its opposite 80 end 33 is connected to the end wall 34 of the casing.

In assembling this mechanism I connect the drum to the clutch member, and connect one end of the coil spiral spring to the 85 drum. This mechanism together with the driving gear and spring 28 are then placed between the side walls 30 and 35 of the casing. The squared shaft portion 13 of the key is then passed through these members 90 tightly fitting the hole 20 in the wall of the drum and the hole 23 in the wall of the clutch member thereby providing a double ring for the drum to firmly support it against all of the strain due to winding the 95 spring and operating the mechanism. This shaft also passes loosely through the gear 25 and the spring 28 and receives its second bearings in the wall 30 of the casing. The outer end 33 of the spring is then passed 100 through the aperture 36 in the casing wall and secured thereto.

It will be noted that by this construction, this device is extremely simple yet strong and durable and owing to its simple construction is quite inexpensive to make which is a most essential feature in mechanical toys in order to enable them to be produced at a 105 marketable figure.

The jack shaft 15 which is driven through 110

the pinion 16 may be provided with crank ends or any other means of producing motion to the parts of the toys.

To start the mechanism in operation it is 5 only necessary to hold the jack shaft or mechanism connected thereto, while the spring is being wound by the rotating of the key.

I claim:

- 10 A spring motor comprising a casing having walls between which the operating mechanism is mounted, a coil spring having one end fixed to one of said walls, a winding key having a shaft with bearings in said 15 walls, a spring winding drum mounted on and arranged to be rotated by said shaft and

having ratchet teeth on one edge thereof, a driving gear receiving a bearing on said shaft and having apertures therein engaged by said drum teeth, and a positioning spring 20 between one of said walls and said gear for pressing the latter into engagement with said teeth, whereby the turning of the key rotates the drum to wind the coil upon it to impart motion to said gear.

25

In testimony whereof I affix my signature in presence of two witnesses.

EPHRIAM J. SCOTT.
